DESIGN FOR A PHOTOCOPY MACHINE

Frederick S. Floeter, Saginaw, Mich., assignor to Wickes Bros., Saginaw, Mich.

Application September 24, 1945, Serial No. 122,317

Term of patent 14 years

(Cl. D64—11)

To all whom it may concern:

Be it known that I, Frederick S. Floeter, a citizen of the United States and a resident of Saginaw, in the county of Saginaw and State of Michigan, have invented a new, original, and ornamental Design for a Photocopy Machine, of which the following is a specification, reference being had to the accompanying drawing, forming a part thereof.

In the drawing:

Fig. 1 is a front perspective view of a photocopy machine showing my new design.

Fig. 2 is a top plan view thereof.

Fig. 3 is an end-elevational view.

I claim:

The ornamental design for a photocopy machine as shown.

FREDERICK S. FLOETER.
